UNITED STATES PATENT OFFICE.

KATHARINE ANNA KLOPF, OF ELIZABETH, ILLINOIS.

BOOK CONTAINER.

Application filed August 1, 1921. Serial No. 488,813.

To all whom it may concern:

Be it known that I, KATHARINE ANNA KLOPF, a citizen of the United States of America, and a resident of Elizabeth, county 5 of Jo Daviess, and State of Illinois, have invented certain new and useful Improvements in Book Containers, of which the following is a specification.

The main objects of this invention are 10 to provide an improved form of holder for visibly supporting a cook book during its use and protecting the book from spattering of material worked upon in the vicinity of the container; and to provide means within the 15 holder for retaining the book in an open position but which is movable to a position where it bears against one of the side walls so as not to be in the way when the container is used for the temporary storage of cakes 20 or other bakery goods.

An illustrative embodiment of this invention is shown in the accompanying drawings, in which—

Fig. 1 is a perspective view of the holder 25 showing in dotted outline a book supported therein.

Fig. 2 is a longitudinal sectional view of the holder taken on the line 2—2 of Fig. 1.

Fig. 3 is a fragmentary transverse section 30 view taken on the line 3—3 of Fig. 1.

The present invention is adapted for use wherever it is desirable to protect a book or other record against dust, and also where it is desired to protect the record against 35 damage by chemicals, as for instance, in a laboratory where valuable records are sometimes accidentally destroyed during their use.

In the form shown, the holder comprises 40 a box-like structure 1, preferably formed of sheet-metal so as to be light in weight, yet rigid in construction.

The top of the holder is in the form of a transparent plate 2, of glass or other suitable 45 material, through which the record is observed. One of the side walls 3 of the container is hinged to the bottom 4, and is provided at its upper edge with a slot 5, for engagement with a catch 6, secured to the 50 frame 7 which supports the glass plate.

Located within the container and secured to brackets 8 mounted on the side walls 9 adjacent the hinged section, is a pair of oppositely disposed spring clips 10, which are

formed to provide clamping parts 11 normally urged against the side walls 9 and arranged to firmly grip the leaves of a book 12 or other record between the clip and the bottom 4.

In order that the interior of the container be free from obstruction when it is used as a storage receptacle, the clamping parts 11 are spaced above the bottom 4 so as to be free to swing into engagement with the side walls when the record is removed.

In operation, the hinged section 3 is opened to permit the insertion of the record between the clips 10 and bottom 4 of the container. The door 3 is then closed so as to protect the record against dust or spattering of material worked upon in the vicinity of the container. When the record is removed, the clamping parts 11 swing downwardly and outwardly into engagement with the side walls 9, and the holder may then be used as a receptacle for the temporary storage of bakery goods to prevent them from becoming dry.

Although but one specific embodiment of this invention has been herein shown and described, it will be understood that certain details of the construction shown may be altered or omitted without departing from the spirit of the invention as defined by the following claims.

I claim:

1. A book container of the class described, comprising a box-like structure having a transparent top member, and a resilient element located within said container and having a clamping part normally urged against one of the side walls of said structure, said clamping part being movable inwardly to a position permitting the insertion of a book between said clamping part and the bottom of said box-like structure.

2. A book container of the class described, comprising a box-like structure having a transparent top member, and a spring secured to one of the side walls of said box-like structure and having a clamping part normally urged against said one wall, said clamping part being movable inwardly to a position permitting the insertion of a book between said clamping part and the bottom of said box-like structure.

3. A book container of the class described, comprising a box-like structure having bot-

tom and side walls and a transparent glass top, one of said side walls being hinged to said bottom, and a pair of oppositely disposed springs secured to the side walls adjacent to said hinged wall, said springs being located within the box-like structure and having clamping parts normally urged against said

adjacent side walls, said clamping parts being movable inwardly to a position permitting the insertion of a book between said 10 clamping parts and bottom wall.

Signed at Chicago this 18th day of July, 1921.

KATHARINE ANNA KLOPF.
